RETACKING MACHINE

Victor E. Zackerson, Alameda, Calif., assignor of
one-half to Ralph W. Jensen

Application August 16, 1946, Serial No. 691,111

4 Claims. (Cl. 1-1)

1

My invention relates to machines and more particularly to a retacking machine for renovating rasp bands or the like.

A rasp band to which my invention pertains is a cylinder of sheet metal perforated on the bias to receive a plurality of tacks which are held against falling out partly by friction, but for the most part by an internal cylinder bearing against the heads of such tacks.

The band is utilized in the roughing up of tire casings in preparation for recapping of the same. After a period of use such tacks become dull and bent and in renovating the bands, such band must be disassembled, the old tacks removed and new ones substituted. In substituting the new tacks, the burrs around the tack openings are first flattened, following which new tacks are inserted by hand into the openings, and are then driven home.

The perforations may be on a right or left-hand bias, in either case making an angle of around 57° with the horizontal, though such angle is not critical.

Among the objects of my invention are to provide a novel and improved machine for use in retacking rasp bands or the like; and to provide a new and improved machine of simple design for simultaneously driving home a plurality of tacks in sheet metal or the like but adapted particularly for the driving home of tacks in a rasp band or the like after such tacks have been inserted into openings manually.

Additional objects of my invention will be brought out in the following description of a preferred embodiment of the same taken in conjunction with the accompanying drawings wherein—

Figure 1 is a side elevational view of my machine illustrating its mode of operation;

Figure 2 is a fragmentary view looking into the front end of such machine;

Figure 3 is a detail in the construction of the machine of Figure 1;

Figure 4 is a plan view of an anvil utilized in the machine of Figure 1;

Figure 5 is a view corresponding to that of Figure 4 but showing a rasp band in position on the anvil.

Referring to the drawings for details, the machine involves a frame 1 including a base 3 and a vertically disposed arcuate arm 5 at one end of the base, the frame being formed of a pair of similarly shaped members 7 held in spaced relationship by an anvil 9 inserted between the base components of the frame and bolted therein.

2

Such anvil terminates somewhat above the base of the frame in a plurality of spaced aligned projections 11 which are diamond-shaped in cross section, with their upper surfaces lying in a common plane.

The diamond-shaped projections are formed by milling intersecting slots across the face of the anvil at angles corresponding to the right and left hand bias of the tack holes in rasp bands. This adapts the machine for use in retacking rasp bands of either the right or left hand bias type without interchanging of anvils. Depending upon the width of the anvil, as many as four transverse rows of tacks may be driven home at one time.

A pressure bar 13 in line with the anvil extends between the frame members 7 and is pivotally mounted therebetween on a pin, preferably an angularly adjustable eccentric 15, such eccentric permitting adjustability of the pressure bar to parallelism with the anvil in the pressure exerting position of the bar.

Manipulation of the pressure bar is accomplished through a bell crank lever 17 pivotally mounted at its fulcrum point on a pin 19 involving a similar angularly adjustable eccentric passing through the frame members at the upper end of the frame. One arm of the lever terminates in an operating handle 21, the other end of this lever being connected by a pair of parallel disposed links 23 to an intermediate point on the pressure bar 13. Such eccentric provides a means for adjusting the pivot position of the bell crank lever 17 to permit such previously mentioned adjustments of the pressure bar.

Both adjustments are accordingly necessary to assure uniformly distributed downward pressure between the pressure bar and the anvil, with the work intermediately disposed on the anvil. Such uniformly distributed pressure is important for in the absence thereof, certain of the tacks are apt to be incompletely assembled, and such condition will not only leave such tacks loose and therefore inefficient as rasp elements, but the existence of such incompletely assembled tacks will render it very difficult for the aforementioned inner cylinder to efficiently hold other tacks from working themselves loose during subsequent use of the rasp band for its intended purpose.

In utilizing the machine, tacks 29 are manually inserted into those openings 31 in a band 33 which were previously occupied by the old tacks. The band is placed on the anvil and due to the relatively large number of holes, a substantially transverse row of tacks will register with the

spaces between the diamond shaped projections of the anvil, in spite of the fact that the actual rows are on the bias. With the band disposed on the anvil, the handle is manipulated downwardly to bring the pressure bar down against the heads of the tacks with sufficient pressure to drive them home. This procedure is followed around the band until all the tacks are in, following which an inner cylinder 35 is added and the band is then again ready for use.

From the above description of a preferred embodiment of my invention, it will become apparent that it fulfills all the objects previously recited therefor, and while I have described the one embodiment in its preferred form, the same is subject to alterations and modification without departing from the underlying principles thereof and I, accordingly, do not desire to be limited in my protection to the specific details illustrated and described, except as may be necessitated by the appended claims.

I claim:

1. A retacking machine for rasp bands or the like comprising a frame including a base and an upright arcuate arm adjacent an end of said base; means on which work is to be supported; pressure means pivotally secured to said upright arcuate arm in cooperative relationship to said work support means, said pressure means including a pressure bar pivotally supported on a pin through the upright arcuate arm of the frame for engaging work positioned on said anvil; and means for manipulating said pressure means in the direction of said anvil.

2. A retacking machine for rasp bands or the like comprising a frame including a base and an upright arcuate arm adjacent an end of said base, said frame being formed of a pair of similarly shaped members; means on which work is to be supported, said means including an anvil disposed between the base portions of said frame members and secured therein, and terminating above said base portions is a plurality of spaced aligned projections having upper surfaces in a common plane; pressure means pivotally secured to said upright arcuate arm in cooperative relationship to said work support means, said pressure means including a pressure bar extending between said frame members and pivotally supported on a pin through the upright arcuate arm of the frame; and means for manipulating said pressure means in the direction of said anvil.

3. A retacking machine for rasp bands or the like comprising a frame including a base and an upright arcuate arm adjacent an end of said base; means on which work is to be supported; pressure means pivotally secured to said upright arcuate arm in cooperative relationship to said work support means, said pressure means including a pressure bar pivotally supported on a pin through the upright arcuate arm of the frame; and means for manipulating said pressure means, said means including a bell crank lever pivotally secured to the upper end of said frame, a handle affixed to one arm of said lever and a link interconnecting the other arm of said lever to said pressure means.
4. A retacking machine for rasp bands or the like comprising a frame including a base and an upright arcuate arm adjacent an end of said base, said frame being formed of a pair of similarly shaped members; means on which work is to be supported, said means including an anvil disposed between the base portions of said frame members and secured therein, and terminating above said base portions is a plurality of spaced aligned projections each of diamond cross-section; pressure means pivotally secured to said upright arcuate arm in cooperative relationship to said work support means, said pressure means including a pressure bar extending between said frame members and pivotally supported on a pin through the upright arcuate arm of the frame; and means for manipulating said pressure means, said means including a bell crank lever pivotally secured to the upper end of said frame, a handle affixed to one arm of said lever and a link interconnecting the other arm of said lever to said pressure means.
